(57) **CLAIM**

The ornamental design for a speaking tube for a stroller, as shown and described.

DESCRIPTION

FIG. 1 is a perspective view of a speaking tube for a stroller showing our new design, with an expandable portion partially expanded state;

FIG. 2 is left side plan view of FIG. 1 in which the attachment clips are not shown and the expandable portion is in a collapsed state;

FIG. 3 is a right side plan view thereof;

FIG. 4 is a front plan view thereof;

FIG. 5 is a rear plan view thereof;

FIG. 6 is a top plan view thereof;

FIG. 7 is a bottom plan view thereof;

FIG. 8 is a side view thereof as attached to a stroller;

FIG. 9 is an isometric view of a portion of the speaking tube for a stroller of FIG. 1, showing an optional cover in an opened position;

FIG. 10 is an isometric view of the portion in FIG. 9, showing the optional cover in a closed position;

FIG. 11 is a right side view of the portion in FIG. 10, with the tube removed for illustration;

FIG. 12 is a bottom plan view thereof;

FIG. 13 is a front plan view thereof; and,

FIG. 14 is a rear plan view thereof.

The broken lines showing the clips in FIGS. 1 and 8, and the optional cover in FIGS. 9-14 is included for the purpose of illustrating unclaimed subject matter, and the showing of the stroller with user and rider in FIG. 8 is included for the purpose of illustrating environment, and both form no part of the claimed design.
